Franc O. Wood.
BY John Day.
ATTORNEY.

UNITED STATES PATENT OFFICE.

FRANC O. WOOD, OF SOUTH PASADENA, CALIFORNIA.

GARMENT-SUPPORTING BELT.

No. 875,973.

Specification of Letters Patent.

Patented Jan. 7, 1908.

Application filed November 11, 1905. Serial No. 287,749.

To all whom it may concern:
Be it known that I, FRANC O. WOOD, of
South Pasadena, in the county of Los Angeles
and State of California, have invented cer-
5 tain new and useful Improvements in Gar-
ment-Supporting Belts, of which the follow-
ing is a full, clear, and exact description or
specification, reference being had to the
annexed drawings and the letters and figures
10 marked thereon.

My said invention which relates to the
waist suspension of articles of wearing
apparel, has for its object to securely sus-
15 pend such articles from the waist of the
wearer, without compression of the waist,
such as that which is experienced when wear-
ing waist belts such as hitherto have been
used for holding up trousers and drawers
20 without ordinary shoulder braces or sus-
penders.

My said invention is also applicable for
suspending and fastening round the waist,
articles of wearing apparel worn by women,
and without compression such as is due to
25 the methods or means of fastening at the
waist, female wearing apparel at present
used.

My invention consists of a flat belt or band
of such length as is requisite for encom-
30 passing the clothes of the wearer at the waist
region of the abdominal portion of the human
body, and it is provided with fastenings at
each end thereof for enabling the ends to be
engaged with or disengaged from each other.

35 What constitutes my invention is the
application to the inner flat face of a belt or
band of one, two, or more hooks, whereinto
a strap usually constituting a tightening
device at the center of the rear of a pair of
40 trousers, and some kinds of skirts, is entered
or passed, so that the strap is held or sup-
ported vertically flatwise at the rear, and the
application to the inner flat face of the belt
or band, and near the ends thereof, of sus-
45 pending loops which engage with the but-
tons at the front and sides of the articles of
wearing apparel being worn.

On the annexed drawings, Figure 1, is
50 an elevation of my improved belt or band,
showing hooks at the rear for engaging with
the strap of the trousers, or other article of
wearing apparel, and the suspending loops
55 for engaging with the buttons at the front
and side parts of the trousers or other article
of wearing apparel to be worn suspendedly,
and without inconvenient abdominal com-

pression by my said improved belt or band.
Fig. 2, is an enlarged or full sized detail draw-
ing of one form of construction of the fastener,
placed on and fastened to the interior of the 60
belt. This fastener is made of metallic wire.
Fig. 3, is a corresponding view of the fas-
tener shown at Fig. 2, with the difference
that instead of being formed of wire, the
fastener shown at Fig. 3, is formed of a flat 65
piece of leather, vulcanite, thin metal, or any
other suitable material. Fig. 4, is an eleva-
tion of a part of the interior face of the belt
or band, showing one of the rear fastening
hooks and a portion of the rear tightening 70
belt of a pair of trousers placed therein.
Fig. 5, is a transverse section of the belt and
fastener on the dotted line a, a, Fig. 4. Fig.
6, is a front elevation of a portion of the ab-
dominal region and legs of the human body, 75
showing my new or improved belt or band
applied thereto for the fastening and suspen-
sion around the waist, and without compres-
sion, by my new or improved belt or band.
Fig. 7, is a rear elevation of a portion of the 80
abdominal region and legs of the human
body, showing the rear tightening belt of
the trousers placed in the hooks at the rear
of the trousers or other article of wearing
apparel.

85 With reference to the foregoing drawings,
the belt or band itself is marked A. At one
end thereof, the buckle B, is fastened by
sewing or riveting, or otherwise, and at the
other end holes C, are formed for engaging 90
with the tag D, of the buckle, when the belt
or band is fastened around the human body
for the purpose of suspending the article or
articles of wearing apparel to be attached
thereto. At or near the center of length of 95
the inside face of the belt or band A, the
hooks E, E, are fastened, as shown at Figs. 1;
4, and 5, and at those portions of the inner
face of the said belt or band situated between
the central rear portion and the ends of the 100
belt, the wire loops F, F, F, F, are fastened,
as shown at Fig. 1, and at Fig. 2. By pref-
erence these hooks F, F, F, F, are each con-
structed with two loops, c, c, and there are
two pairs of such fastenings F, at each end of 105
the belt or band, as shown at Fig. 1. The
object for placing two of each of the loop
fastenings F, at each end of the inner face of
the belt or band, is to render easy the entry
of the buttons shown in dotted lines marked 110
G, and H, respectively, at Figs. 2 and 3, also
shown dotted on a smaller scale at Fig. 6.

By providing such number of loops C, the buttons G, and H, fastened to the wearing apparel are slipped downwards into the space between the leather of the belt or band 5 A, and the fastening F, Figs. 1 and 2, or into the corresponding loops in the fastening of different material, shown at Fig. 3.

It is to be understood that it is not essential to use a buckle and fastening holes for 10 joining the ends of the belt or band, as any of the numerous other belt fasteners commonly known and used, may be used instead of the fastening illustrated by the annexed drawings.

Having now described the nature of my 15 said invention, and the best system, mode or manner I am at present acquainted with for carrying the same into practical effect, I desire to observe in conclusion that what I 20 consider to be novel and original, and therefore claim as the invention to be secured to me by Letters Patent, is as follows:

The wearing apparel abdominal suspending device, consisting of the combination of a 25 flat flexible belt or band having rear attach-

ments of upturned hooks and lateral-frontal attachments each consisting of rigid duplex looped engagers for the buttons between the front and rear of the belt or band, the front attachments having two entrances at the top 30 thereof, the rear and front attachments being arranged so that they respectively engage with the rear strap and buttons at the fronts and sides of trousers and other articles of wearing apparel, and being rigidly constructed and fastened preventing horizontal sliding movement of the buttons so that one or more articles of wearing apparel may be suspended upon the abdominal region of the human body without compression of the abdomen, substantially as described.

In testimony whereof, I, the said FRANC O. Wood, have hereunto set my hand and seal at Los Angeles aforesaid, in the presence of two subscribing witnesses.

FRANC O. WOOD. [L. s.]

Witnesses:
